UNITED STATES PATENT OFFICE.

WILLIAM GORDON, OF BOSTON, MASSACHUSETTS, ASSIGNOR, BY DIRECT AND MESNE ASSIGNMENTS, TO ARTHUR FULLER, TRUSTEE, OF SAME PLACE.

SOLE-EDGE-BURNISHING MACHINE.

SPECIFICATION forming part of Letters Patent No. 364,585, dated June 7, 1887.

Application filed January 8, 1887. Serial No. 223,725. (No model.)

To all whom it may concern:

Be it known that I, WILLIAM GORDON, of Boston, in the county of Suffolk and State of Massachusetts, have invented certain new and useful Improvements in Sole-Edge-Burnishing Machines, of which the following is a specification.

This invention relates to boot and shoe sole edge machines; and it consists in the improvements hereinafter described and set forth.

Of the accompanying drawings, forming a part of this specification, Figure 1 represents a front elevation of the machine. Fig. 2 represents a side elevation of the same. Fig. 3 represents an enlarged section on line *xx*, Fig. 1. Fig. 4 represents an enlarged section on line *yy*, Fig. 1.

The same letters of reference indicate the same parts in all the figures.

20 In the drawings, *a* represents the frame or pedestal of an edge-burnishing machine. *b* represents the driving-shaft journaled in bearings at the upper part of said pedestal. On said shaft are formed two eccentrics, *d d*, having their centers at diametrically opposite sides of the center of the shaft. On said eccentrics are swiveled blocks *g g*, which are fitted to slide in slots *h*, formed in the upper ends of two levers, *i i*. Said levers are mounted, 25 respectively, on studs *j j*, affixed to the pedestal *a*, and are socketed at their lower ends to receive the shanks *k* of sole-edge-burnishing tools *k'*, each lever having a tool. The shanks of said tools are adapted to slide in said sockets, 30 and are pressed downwardly therein by springs *m* as far as pins *n* on said shanks, abutting against stops in the sockets, will permit. The tools are thus adapted to yield, as will be readily seen.

40 The rotation of the driving-shaft causes the eccentrics *d d* to oscillate the levers *i i* and reciprocate the burnishing-tools *k' k'* simultaneously in opposite directions. The lever *i* is bent or offset, as shown in Fig. 2, so that 45 while the upper ends of the levers vibrate in different planes, to accommodate the two eccentrics on the driving-shaft, their lower ends, having the burnishing-tools, vibrate in the

same plane, and therefore act simultaneously on a sole-edge held against them by the operator.

50 It will be seen that the two tools, acting simultaneously, burnish more rapidly than a single tool, the work performed in a given time being nearly equal to that performed by two machines having only one tool each, while only one operator is required.

55 To prevent the burnishing-tools from swiveling or turning too loosely, I provide the levers *i* with downwardly-projecting lips *l*, which are close to the rear sides of the tools and prevent the tools from turning, so that their lips will stand across the line of their movement.

60 *r* represents a lever pivoted to ears on the outer side of one of the levers *i*, and having on its lower end a socket, which receives the shank of a burnishing-tool, *r'*, formed to act on the shank-edge of a sole, the tools *k' k'* being formed to act on the fore-part edge. The lever *r* is normally held in the position shown in Fig. 4, so that it will not be in the way during the fore-part-burnishing operation, by a spring, *s*. When the operator desires to use the tool *r'*, he engages the shank-edge with the longer lip of said tool and draws the latter outwardly to a convenient distance from the lever *i*. After the shank-edge is burnished the spring *s* forces the tool *r'* inwardly and prevents it from swinging loosely.

65 I claim—

1. In a sole-edge-burnishing machine, the combination of the supporting-frame, the driving-shaft journaled therein and having two oppositely-projecting eccentrics, *d d*, the tool-carrying lever *i*, independently pivoted on a center, *j*, and engaged at its upper end with one of said eccentrics, the tool-carrying lever *i'*, independently pivoted in a different plane on another center *j*, engaged at its upper end with the other eccentric and bent or offset to bring its tool-carrying end into the same operative plane with the tool end of the lever *i*, substantially as set forth.

2. In a machine having the tool-carrying levers *i i*, arranged with their tools in the same

plane, and their operating mechanism, the combination, with one of said levers, of the lever *r*, pivotally connected with the lever *i*, and having a shank-edge-burnishing tool arm *s* ranged at one side of the plane in which the levers oscillate. In testimony whereof I have signed my

name to this specification, in the presence of two subscribing witnesses, this 24th day of December, A. D. 1886.

WILLIAM GORDON.
